(57) CLAIM

I claim the ornamental design for a footwear upper, as shown and described.

DESCRIPTION

FIG. 1 is a perspective view of an footwear upper showing the new design.

FIG. 2 is a left side view of the footwear upper showing the new design.

FIG. 3 is a right side view of the footwear upper showing the new design.

FIG. 4 is a front view of the footwear upper showing the new design.

FIG. 5 is a rear view of the footwear upper showing the new design.

FIG. 6 is a top plan view of the footwear upper showing the new design; and,

FIG. 7 is a bottom plan view of the footwear upper showing the new design.

The broken lines shown in the drawings are to illustrate environment, namely, portions of an footwear upper bearing the claimed design, and form no part of the presently claimed design. The shading lines shown in the drawings represent the approximate three-dimensional contour of the design, and are not intended to indicate surface decoration.
